(57) **CLAIM**

The ornamental design for a front portion for a motor vehicle, as shown and described.

DESCRIPTION

FIG. 1 is a front left perspective view of a front portion for a motor vehicle showing our new design;

FIG. 2 is a rear left perspective view thereof;

FIG. 3 is a front right perspective view thereof;

FIG. 4 is a rear right perspective view thereof;

FIG. 5 is a front view thereof;

FIG. 6 is a rear view thereof;

FIG. 7 is a right side view thereof;

FIG. 8 is a left side view thereof; and,

FIG. 9 is a top view thereof.

The de-emphasized and halftone portions shown in the figures illustrate environmental structure of the front portion for a motor vehicle that forms no part of the claimed design. The bottom view of the front portion for a motor vehicle forms no part of the claimed design.
